Attorney

UNITED STATES PATENT OFFICE

MICHAEL RUSSIAN, OF BINGHAMTON, NEW YORK

SAFETY LOOP FOR BRAKE BEAMS

Application filed March 12, 1929. Serial No. 346,407.

My invention relates to an improvement in safety loops for brake beams on railroad cars, and it has for its object an easily constructed and easily mounted device, whereby the falling of a brake beam from any defect or cause is avoided, and the constant possibility of derailment of the train is prevented. A further object of my invention is to provide a safety loop which will permit the ready replacement of a new bar or beam with the least amount of labor and delay.

With these objects in view my invention consists of certain novel features of construction and arrangement of parts as are more clearly hereinafter described and pointed out in the claims, reference being had to the accompanying drawing, in which:

Fig. 1 is a side view of my device in perspective, as applied to a railroad truck.

Fig. 2 is a side view of my device.

Fig. 3 is a rear view of my device.

Fig. 4 is a perspective view of a detailed part of my device.

The same reference characters denote like parts in each of the several figures of the drawing.

In carrying out my invention, I provide a frame A, constructed preferably of heavy flat bent iron, the same being bent into a double fold at Y, and thereby projected into two parallel folds adjacent to each other Y¹, Y², projecting into a neck formation w. From the bend the one folded portion Y¹ extends in vertical alinement downward, the opposite adjacent fold Y² extends for a space downward in vertical alinement, and then projects into a sloping alinement Y³ as indicated on the drawing.

Thru the adjacent parallel folds at the top Y¹ and Y², I have two or more bolt openings b, b, while the lower end of the vertical portion Y¹ is projected into an offset formation 4, and thru which formation I have the elongated opening 5. The opposite sloping portion projected from the end of the slope projects for a space 3", vertically downward, and thru this vertical projection I have an additional opening 6. Loosely mounted in said openings 5 and 6, I have the rod cross lock bar B, one end of which in

position extends horizontally in a curved hooked projection 7, while the opposite end of bar B may be provided with an angular bent portion 8 which tends generally to assume a substantially vertical position when in operative engagement. Thru the openings b, b in the neck w there is mounted the bar B, whereby the frame A can be easily mounted against the cross beam C, on the truck or other part of the truck in any convenient manner. By virtue of the construction of the locking bar B having the end 7 terminating in the hook formation, when the locking bar is in operative position the end 8 being larger and heavier than the end 7 will tend to rotate the rod B on its longitudinal axis by gravity so that the end 8 tends to assume a vertical position and the hook projection 7 a substantially horizontal position. Thus the bar 8 becomes automatically locked in position and will not fall out. In operation, two frame members, A, spaced apart, are vertically mounted, parallel to each other on the car truck frame C. The locking bars B being removed and the beams having been placed in position, the locking bars are then inserted in the openings 5 and 6 and turned into locked position, as shown in Figure 1, with the hooked ends 7 extending outwardly and the bent end 8 extending downwardly. If for any reason the brake beam D is broken or drops down, it comes in contact with and rests upon the parallel lock bars B, in the parallel supporting frames A, A and is there held and out of contact with the parts of the truck. The lock bars B are then unlocked and withdrawn and the broken parts of the brake rod D removed and easily replaced by a new one with little labor or interference with the parts. The bars B are then again replaced in locked position in the frame for further protecting support.

Having thus described my invention, what I claim as new and for which I desire Letters Patent is as follows:

1. In a loop support for brake bars, two triangular metal frame formations adapted to be mounted on either side of a truck, and adapted to receive within the triangular por-

tion the brake beam, the upper portion of the triangular formation provided with openings, bolts passing through said openings for securing the triangular formations to the car truck, and a locking bar constituting the base of the triangular formation and removably mounted in the lower ends of the sides of the triangular formation.

2. A loop support for brake bars comprising a single strip of metal bent upon itself with the bent portion terminating in a hook formation for engaging the upper surface of a car truck frame, the bent portion of the metal strip extending downwardly in parallel relation with one part being vertical and provided with an offset end having an opening therein, the other part diverging with its end terminating in a vertical portion provided with an opening in line with the opening of the offset portion, and a locking bar passing loosely through said openings and provided with means to be acted upon by gravity to maintain the locking bar in locked relation.

25 3. A loop support for brake beams and the like comprising a frame open at its bottom, means for securing the frame to a car truck, and a rod inserted in the frame to close the bottom opening, said rod being automatically locked by gravity, in its operative position.

4. A safety support for brake beams comprising an open frame to receive the brake beam, means to secure the frame to a car truck, and a rod constituting a closure for the open frame, said rod being inserted in the frame and locked by gravity, in operative position.

40 5. A safety support for brake beams comprising a frame having sides and an open bottom, means for securing the frame to a car truck, and a locking rod inserted through aligning openings in the sides of the frame, a hook on one end of the rod to prevent withdrawal of the rod when in operative position, and a weighted member at the other end of the rod to turn the latter into locked position.

In testimony whereof I have affixed my signature.

50 MICHAEL RUSSIAN.
